United States Patent Office

Des. 183,173
Patented July 8, 1958

183,173

CONTROL MACHINE FOR RAILWAY CONTROL OR SIMILAR ARTICLE

John W. Logan, Jr., Forest Hills, and Robert A. Woods,
Verona, Pa., assignors to Westinghouse Air Brake
Company, Wilmerding, Pa., a corporation of Penn-
sylvania

Application March 14, 1957, Serial No. 45,251

Term of patent 14 years

(Cl. D26—5)

Fig. 1

Fig. 2.

Fig. 3.

Fig. 4.

Fig. 5.

Fig. 1 is a front perspective view of a control machine for railway control or similar article, showing our new design;

Fig. 2 is a top plan view;

Fig. 3 is a front elevational view;

Fig. 4 is a vertical cross-sectional view taken on line 4—4 in Fig. 2; and

Fig. 5 is a horizontal cross-sectional view taken on line 5—5 in Fig. 3.

The lower part of the front and back of the machine consists of six panels similar to those shown in Fig. 1. The representative surface controls in Fig. 1 have been omitted in Figs. 2, 3, and 4 for convenience in illustration.

We claim:

The ornamental design for a control machine for railway control or similar article, as shown and described.
